UNITED STATES PATENT OFFICE.

NAPOLEON A. MONFILS, OF HAVERHILL, MASSACHUSETTS.

HEEL.

1,401,808.

Specification of Letters Patent. Patented Dec. 27, 1921.

Application filed November 8, 1920. Serial No. 422,606.

To all whom it may concern:

Be it known that I, NAPOLEON A. MONFILS, a citizen of the United States, residing at Haverhill, in the county of Essex and State 5 of Massachusetts, have invented certain new and useful Improvements in Heels; and I do declare the following to be a full, clear, and exact description of the invention, such as will enable others skilled in the art to 10 which it appertains to make and use the same.

This invention relates to improvements in heels for shoes, and has more particular reference to ladies' wooden heels known as 15 "French" heels, although it is not to be restricted to this particular type of heel.

Heels of the above mentioned type are very liable to breakage owing to the peculiar construction which embodies a central 20 portion of relatively small cross-section. Consequently, when the heel is struck against solid objects such as curb stones and cobble stones, it is very easily broken and rendered useless.

It is therefore the principal object of this 25 invention to overcome the above mentioned difficulty by the provision of a heel of the type under consideration embodying a relatively large metallic reinforcing pin which 30 constitutes a permanent part of the heel and prevents possible breakage of the latter.

Another and very important object of the 35 invention is to provide a reinforced heel which is an improvement over prior devices of this class, the reinforcing pin being, according to this invention, of tubular form and being preferably composed of comparatively soft metal so as to not only function in reinforcing the heel, but also to serve as a 40 means for coaction with the usual fastening screw of a rubber lift which may be applied to the bottom of the heel, the soft metal permitting said attaching screw to become effectively engaged with the interior surface 45 of the pin without the necessity of equipping the latter with internal screw-threads or the like.

Still another object of the invention is to 50 provide a heel embodying the above referred to hollow reinforcing pin which is held in place partially by means of beads at its opposite ends which serve to compress the fibers

of the wood and thereby greatly strengthen the heel, this pin being provided with a plurality of exteriorly arranged longitudinal 55 ribs which assist in anchoring the pin and preventing rotation thereof when the lower bead is being formed and when the attaching screw of the rubber lift is being connected thereto.

Other objects and advantages of the invention will be apparent during the course of the following description.

In the accompanying drawings forming a 65 part of this specification and in which like numerals are employed to designate like parts throughout the same:

Figure 1 is a central vertical sectional view through a heel constructed in accordance 70 with this invention.

Fig. 2 is a section taken at approximate right angles on the line 2—2 of Fig. 1.

Fig. 3 is a horizontal section taken on the plane of the line 3—3 of Fig. 1.

Fig. 4 is a detail view of the reinforcing 75 pin provided at one end with a bead.

Fig. 5 is a detail view of the lower portion of the heel showing the manner in which 80 a lift is connected to and associated with my heel.

Referring to the drawings, wherein the preferred embodiment of the invention is clearly illustrated, it will be seen that the numeral 1 designates a ladies' wooden heel of "French" type which is here shown as 85 being provided with a centrally disposed vertical bore 2 which extends entirely therethrough and is provided at its opposite ends with counterbores 3 the bottoms of which are formed with endless beads. Arranged in 90 this bore is a reinforcing pin 4 of tubular formation. It may be mentioned that this pin is preferably composed of comparatively soft metal for an important purpose to be hereinafter described. At its opposite ends 95 this pin is provided with heads or beads 5 which coact with the beads in the counterbores 3 and serve to retain the pin in position. In addition to being equipped with these retaining beads the pin is also equipped 100 with a plurality of exteriorly disposed anchoring ribs 6 which become automatically embedded in the wall of the bore and prevent rotation of the pin when the lower bead is

being formed. They also serve another function to be hereinafter set forth.

In carrying out the invention, the heel is clamped in a jig which is attached to a table or the like on which there is a high speed drill press, the attaching end of the heel being positioned uppermost. When in this position the bore is drilled at the desired point so as to permit insertion of the tubular reinforcing pin. After the bore 2 has been drilled, a suitable countersink tool is employed to form the counterbores and beads 3 at the opposite ends of the bore 2. The heel is then ready for insertion of the reinforcing pin, which in actual practice, is cut from lengths of metal tubes provided with the opposed longitudinal anchoring ribs. It is to be noted that the pins thus cut should be of a length slightly greater than the length of the heel bore. Having cut the pins into the desired lengths, each one is provided, by the means of a suitable beading tool, at the one end with an anchoring flange or bead referred to as 5. Now, by inserting the tube downwardly through the bore and placing it in the position disclosed in the drawings, the unbeaded end of the latter can likewise be provided with an anchoring flange or bead. At this point I wish to mention, that with this construction, the fibers of the wood will be compressed to a considerable extent and the heel will be greatly strengthened. It is to be noted that the anchoring ribs 6 automatically embed themselves in the wall of the bore when the reinforcing pin is being driven downwardly through the latter, and, as before stated, they prevent rotation of the pin while the lower bead is being formed and they constitute additional means for reinforcing the pin itself. Furthermore, since the anchoring ribs 6 are comparatively long, they are permitted to serve an additional and important function. For instance, should the heel be split or broken on a transverse line, that portion which becomes separated from the body portion will be prevented from rotating with respect to the body portion and thus properly held in place, this result being brought about the employment of the aforementioned ribs which serve to prevent rotation of the separated part of the heel. Therefore, even if the heel does get broken, it may be used for quite sometime in such a state, as the reinforcing pin and anchoring ribs serve to prevent separation and rotation of the broken parts and the usual covering employed serves to hide the break or crack. After the article is completed it has the general appearance of heels now on the market, and it is to be noted that my construction and arrangement does not in any way interfere with the easy and ready attachment of the heel to a shoe. As a matter of fact, it assists in permitting effective and easy attachment of a rubber lift or the like

which is usually connected to the bottom of the heel. The manner in which the rubber lift is associated with and connected to my heel is clearly disclosed in the detail view of Fig. 5. Attention is again directed to the fact that the reinforcing pin is preferably composed of comparatively soft metal so that when the fastening screw of the lift is placed in position and forced into the lower end of the pin, the threads thereof will cut into the interior wall of the pin and the screw thus be engaged with the pin and in this way retain the lift in position. This manner of attaching a lift will be found extremely advantageous in that it will overcome the necessity of securing the rubber lift by means of nails and other fastenings which may possibly split the heel during the attaching operation. Emphasis is to again be laid on the employment of the anchoring ribs 6 which during the attachment of the lift prevent the rotation of the pin and thus insure effective engagement of the attaching screw of the lift with the reinforcing pin which could not be effectively accomplished if the pin was permitted to rotate.

From the foregoing description, it will be seen that I have devised an extremely advantageous heel which is an improvement over prior devices of this kind, one which is extremely strong and durable and owing to its simplicity, is very inexpensive to both the manufacturer and the user. The construction which I employ will not add to the weight of the heel and in view of the proportions of the reinforcing means with respect to the heel proper, it will be seen that there is little or no chance of the heel becoming accidentally broken when struck against solid objects. These and other advantages and features of the invention have, no doubt, become apparent during the foregoing description.

While I have shown and described my improved reinforcing pin as used in connection with a wooden heel, I desire to be understood that it may be used to an advantage with heels constructed of other material.

Since probably the best results may be obtained with the construction and arrangement shown and described, this construction and arrangement is taken as the preferred embodiment of the invention. However, I wish it to be understood that the various minor changes in the shape, size, and arrangement of parts may be resorted to without departing from the spirit of the invention or the scope of the subjoined claim.

I claim:

As an article of manufacture, a heel provided with a centrally disposed vertical bore extending therethrough, being uniform in diameter and provided at its opposite ends with counterbores, the bottoms of which are formed with beads, and a tubular reinforcing

pin fitting snugly in said bore and having
rolled anchoring and retaining flanges
formed at its opposite ends and coöperative
with the beads in said counterbores, said
5 flanges having the additional function of
compressing the fibers of the heel between
them to decidedly reinforce the heel, said

pin being provided with a longitudinal ex-
teriorly disposed anchoring rib of consider-
able length embedded in said heel and serv- 10
ing the several functions described.

In testimony whereof I have hereunto set
my hand.

NAPOLEON A. MONFILS.
